Primary Examiner — Karen E Eldridge Powers(74) *Attorney, Agent, or Firm* — Cantor Colburn LLP(57) **CLAIM**

The ornamental design for an adjustable brush handle, as shown and described.

DESCRIPTION

FIG. 1 is a first, bottom perspective view of an adjustable brush handle according to the present disclosure;

FIG. 2 is a second, bottom perspective view of the adjustable brush handle of FIG. 1;

FIG. 3 is a first, top perspective view of the adjustable brush handle of FIG. 1;

FIG. 4 is a second, top perspective view of the adjustable brush handle of FIG. 1;

FIG. 5 is a bottom plan view of the adjustable brush handle of FIG. 1;

FIG. 6 is a top plan view of the adjustable brush handle of FIG. 1;

FIG. 7 is a first side elevation view of the adjustable brush handle of FIG. 1, the opposite side being identical thereto; and,

FIG. 8 is a second side elevation view of the adjustable brush handle of FIG. 1, the opposite side being identical thereto. The broken lines shown in the drawings illustrate features of the article in which the design is embodied that form no part of the claim.
